SUPERREGENERATIVE RECEIVER

Walter van B. Roberts, Princeton, N. J., assignor
to Radio Corporation of America, a corporation
of Delaware

Application March 30, 1929, Serial No. 351,411
Renewed June 22, 1931

35 Claims. (Cl. 250—20)

The present invention relates to regenerative systems, and, more particularly, to a novel method of, and means for, producing super-regeneration in a receiving circuit.

5 In the well known type of super-regenerative receiving systems there exists a defect which has handicapped their wide-spread use. It is known that one of the disadvantages of the super-regenerative receiving circuit is the fact that when 10 radio frequency feed back is made strong the interrupting super-audible frequency does not fulfill its function completely enough. That is to say, before the full effect of the super audible frequency damping is achieved, the regenerative 15 amplifier tube begins again to build up the incompletely quenched oscillations, producing more or less sustained radio frequency oscillations.

Now, I have discovered a method of positively stopping, during the damping period, oscillations 20 of any strength that may be built up during the amplifying period. The arrangement devised by me to embody this method utilizes a feedback, which I term a reverse feedback, in opposition to the amplifying feedback, and the reversed feedback action is periodically substituted for the 25 regenerative feed back by the interrupting super-audible frequency current.

Accordingly, it is one of the main objects of 30 my present invention to provide a method of, and means for, producing super-regeneration in a receiving circuit which comprises utilizing a reverse feedback action for rapid quenching of radio frequency oscillations during the damping period, without introducing appreciable damping into the 35 oscillation circuit during the regeneratively amplifying, or building up, period.

Another important object of the invention is to provide a receiving circuit of the super-regenerative type in which a pair of triodes of similar 40 characteristics is utilized, one of the triodes functioning as the amplifier and having a feed-back coil associated therewith, the other triode having a second feed-back coil associated therewith and functioning as a reverse feed-back means, the 45 entire operation of the amplifying action being initiated by an interrupting super-audible frequency in such a manner that the reverse feed-back means begins to quench oscillations in the amplifier triode prior to the instant when oscillations of the amplifier would otherwise attain an 50 undesirable amplitude. The novel features which I believe to be characteristic of my invention are set forth in particularity in the appended claims, the invention itself, however, as to both its organization and method of operation will best be

understood by reference to the following description taken in connection with the drawing in which I have indicated diagrammatically one circuit organization whereby my invention may be carried into effect.

50 The illustrated circuit shows a source of super-audible frequency current F coupled to a circuit L, C tuned to the frequency F. The circuit L, C is connected to a pair of triodes 1, 2, of similar characteristics, each of which triodes has inserted in its plate circuit a feedback coil shown by T and T_r, respectively, magnetically coupled to a coil L₁. The grid of each triode is biased, as shown, both grids being, for example, equally biased through high resistance R which is preferably connected to the middle of coil L, and through the common parallel resonant circuit L₁, C₁ to a point on the filament circuits of the triodes 1, 2.

55 The feedback coil T, connected in the plate circuit of triode 1, is connected to the reversed feedback coil T_r, the latter coil being connected in the plate circuit of triode 2. A source of plate potential, and a utilization means, such as phones, are common to the output circuits of the triodes 1, 2. A usual by-pass condenser C₂ is 60 shunted across the phones.

65 The circuit L, C is fixedly tuned to the super-audible frequency F. It will be seen at once that with the arrangement shown, when the grid of triode 1 is less negative than normal, the grid of triode 2 will be more negative than normal. While the grid of triode 2 is very negative, the triode 2 is ineffective. But, it should be noted that the grid of triode 1 is only slightly negative, and, due to the action of feedback coil T and coil 70 L₁, triode 1 builds up oscillations in the radio frequency circuit, the amplitude at a given time depending upon the signal input.

75 Due to the reversing action of the super-audible frequency energy F, the grid of triode 1 next becomes very negative, while the grid of triode 2 becomes only slightly negative. This results in the reverse feedback coil T_r "building down" or positively quenching the oscillations, thus taking 80 the place of ohmic resistance in quenching oscillations at super-audible frequency. It should also be noted that the method described herein allows the use of another tuned circuit loosely coupled to the radio frequency circuit, since the reversed feedback may be increased to such extent as to wipe out residual oscillations in this 85 extra circuit also.

90 In other words, the arrangement I have shown makes it possible to connect a pre-selector circuit as, for instance, a band-pass circuit, or a 95 100 105 110

tuned stage of radio frequency amplification, or an untuned stage of radio frequency amplification, or all three, or any two between the antenna and the radio frequency circuit L_1 , C_1 .

5 The reactions and interactions taking place in the circuit may be illustrated by the following mathematical expressions, the latter serving the purpose of laying down rules of design, whereby anyone, skilled in the art, may construct the 10 circuit of this invention. It can be shown that the feedback from the tickler T is proportional to,

$$a_1 - E \sin Ft$$

15 The feedback from the coil T_r is proportional to,

$$(-a_2 - E \sin Ft)$$

The total feedback, therefore, is equal to,

$$(a_1 - a_2) - 2E \sin Ft$$

20 It is merely necessary to keep the constant term $a_1 - a_2$ of a negative value, or of sufficiently small positive value that it is not enough to completely wipe out the ohmic resistance of the radio frequency circuit, in order to produce the action described heretofore, it being understood that,

25 a_1 =the amount of negative resistance "fed back" to the input circuit in the absence of E ,

a_2 =the amount of positive resistance "fed back" to the input circuit in the absence of E ,

30 E =the maximum extra resistance fed back when the peak voltage of frequency F is applied to the grids.

It is to be observed that a further advantage of this circuit resides in the fact that the voltage of frequency F being differentially applied to the 35 grids, the current through the phones does not vary at frequency F to nearly so great an extent as in the ordinary single tube super-regenerative arrangement, where there must be large currents of interruption frequency through the 40 phones, unless elaborate filtering arrangements are used to separate such currents from the desired signals.

In the drawing it is to be understood that the 45 source of energy to be amplified is coupled or otherwise connected across the coil L_1 .

While I have indicated and described only one system for carrying my invention into effect, it will be apparent to one skilled in the art that my 50 invention is by no means limited to the particular organization shown and described, but that many modifications in the circuit arrangement, as well as in the apparatus employed, may be made without departing from the scope of my invention as set forth in the appended claims.

55 What I claim is:

1. A super-regenerative receiving circuit comprising a pair of triodes of similar characteristics having grid and plate circuits, a tuned circuit common to the grid circuits of both triodes, one 60 of said triodes having its plate circuit coupled to the tuned circuit in its grid circuit, the other triode having its plate circuit reversely coupled to said tuned circuit, and a source of interrupting current coupled to the grid circuits of said triodes said current being of a super-audible frequency.

2. A receiving circuit comprising a triode provided with input and output circuits, the input circuit including a resonant circuit, means for 70 coupling said output circuit regeneratively to the resonant circuit in its input circuit, a second triode provided with input and output circuits, said last named input circuit also including said resonant circuit, means for coupling the last 75 named output circuit regeneratively to said reso-

nant circuit in a reverse manner, a source of interrupting current coupled to said input circuits, the current being of a super-audible frequency, the resonant circuit being tuned to said frequency.

3. A method of operating a super-regenerative receiver provided with an amplifier employing a feedback action and a reverse feedback action which consists in subjecting signal energy to the amplifier employing the feedback action, subjecting the signal energy to the reverse feedback action, in opposition to the amplifying feedback, and periodically rendering the reverse feedback operative thereby positively stopping oscillations of any strength that may be built up during the amplifying period.

4. A method of operating a super-regenerative receiver which consists in subjecting signal energy to an amplifying feedback action, and to a reverse feedback action, in opposition to the amplifying feedback, and periodically rendering the reverse feedback operative thereby positively stopping oscillations of any strength that may be built up during the amplifying period.

5. A method of operating a super-regenerative receiver which consists in feeding the signal energy to the receiver and subjecting signal energy to an amplifying feedback action, supplying an interrupting current of super-audible frequency to the receiver, and utilizing the interrupting current to periodically impress a reverse feedback action, in opposition to the amplifying feedback, for the amplifying feedback.

6. In a super-regenerative amplifier provided with a signal input circuit and an output circuit, the method of maintaining a definite relationship between the amount of damping action during the damping period and the amount of undamping action during the building up period which includes the steps of applying signal energy to the amplifier, feeding back energy from the amplifier output to the input thereof in regenerative phase, feeding back energy to the amplifier input in degenerative phase and periodically and harmonically varying the strength of both feedbacks in inverse sense so that the equivalent single resultant feedback is alternatively regenerative and degenerative in phase.

7. The method of operating a super-regenerative receiver which consists in feeding the signal energy to the receiver and subjecting signal energy to an amplifying feedback action, supplying an interrupting current of super-audible frequency to the receiver, feeding back signal energy, in opposition to the amplifying feedback, and utilizing the interrupting current to periodically substitute the opposing feedback for the amplifying feedback, for rapid quenching of radio frequency oscillations during the damping period.

8. A method of operating a super-regenerative receiver which consists in feeding the signal energy to the receiver and subjecting signal energy to an amplifier employing a feedback action, supplying an interrupting current of super-audible frequency to the receiver, subjecting the signal energy to a reverse feedback action, in opposition to the amplifying feedback, and utilizing the interrupting current to periodically substitute the reverse feedback for the amplifying feedback thereby positively stopping radio frequency oscillations during the damping period.

9. In a feedback circuit, the method of securing great amplification without building up sustained oscillations which comprises periodically reversing the phase of the feedback.

10. The method of amplifying varying electric currents which comprises impressing the varying potential of the current to be amplified upon a feedback circuit and periodically reversing the 5 phase of the feedback whereby super-regenerative action is obtained. 80
11. The method of amplifying varying electric currents which comprises impressing the varying potential of the current to be amplified upon a 10 system including feedback means and counter-feedback means and periodically altering the relation between the amount of feedback and the amount of counter-feedback of the system, whereby super-regenerative action is obtained. 85
15. 12. The method of amplifying varying electric currents which comprises impressing the varying potential of the current to be amplified upon a system including a feedback circuit and a counter-feedback circuit and periodically varying the 20 relation between the amount of feedback and the amount of counter-feedback, at some frequency relatively low as compared to the frequency of the current to be amplified, whereby super-regenerative action is obtained. 90
25. 13. The method of amplifying varying electric currents which comprises impressing the varying potential of the current to be amplified upon a system including a feedback circuit and a counter-feedback circuit and periodically varying the difference 30 between the amount of feedback and amount of counter-feedback whereby super-regenerative action is obtained. 95
35. 14. The method of amplifying varying electric currents which comprises impressing the varying potential of the current to be amplified upon a system including a feedback circuit and also upon a counter-feedback circuit and periodically varying both the amount of feedback and the amount of counter-feedback whereby super-regenerative 40 action is obtained. 100
45. 15. The method of amplifying varying electric currents which comprises impressing the varying potential of the current to be amplified upon a system including feed-back means adjusted near the point of oscillation and a counter-feedback means and periodically varying the relative amounts of feedback and of counter-feedback whereby the net amount of feedback varies periodically about said value which is near the point 50 of oscillation. 105
55. 16. The method of amplifying varying electric currents which comprises impressing the varying potential of the current to be amplified upon a system including a feedback circuit and upon a counter-feedback circuit and periodically varying both the amount of the feedback and the amount of the counter-feedback of said circuits at some frequency relatively low as compared to the frequency of the current to be amplified whereby 60 super-regenerative action is obtained. 110
65. 17. Apparatus for amplifying varying electric energy comprising a thermionic tube having input and output circuits coupled so as to produce a feedback system, a second thermionic tube having input and output circuits coupled so as to produce a counter-feedback system, means for impressing said energy upon both said systems and means associated with both said systems for periodically altering the relation between the 70 amount of feedback and the amount of counter-feedback of said systems. 115
75. 18. Apparatus for amplifying signal modulated high frequency energy comprising a thermionic tube having input and output circuits coupled so as to produce a feedback system, a second thermi- 120
- onic tube having input and output circuits coupled so as to produce a counter-feedback system, said two systems having common input and output circuits and means for periodically varying the relation between the amount of feedback and the amount of counter-feedback at some frequency relatively low compared to the frequency of the current to be amplified. 125
19. Apparatus for amplifying varying electric currents comprising a thermionic tube having input and output circuits coupled so as to form a feedback circuit, a second thermionic tube having input and output circuits coupled so as to form a counter-feedback circuit, said two circuits having common input and output circuits, means for impressing the potential of said currents on said common input circuit thereby causing said feedback circuit to generate oscillations and means for periodically varying the amount of counter-feedback in said counter-feedback circuit thereby stopping the generation of oscillations in said feedback circuit whereby super-regenerative action is obtained. 130
20. Apparatus for amplifying varying electric currents comprising a thermionic tube having input and output circuits coupled so as to form feed-back circuit, a second thermionic tube having input and output circuits coupled so as to form a counter-feedback circuit, said two circuits having common input and output circuits, means for impressing the potential of said currents upon the inputs of both said circuits and means differentially applied to the inputs of said feedback and counter-feedback circuits for periodically varying the amount of counter-feedback in said counter-feedback circuit, said circuits being adapted to generate oscillations in accordance with the action of the feedback circuit and to prevent the generation of oscillations in accordance with the action of the counter-feedback circuit where- 135 by super-regenerative action is obtained. 140
21. Apparatus for amplifying varying electric currents comprising a thermionic tube having input and output circuits coupled so as to form a feedback system, a second thermionic tube 145 having coupled input and output circuits so as to form a counter-feedback system, said systems having common input and output circuits and means for periodically varying both the amount of feedback and the amount of counter-feedback 150 of said system. 155
22. Apparatus for amplifying varying electric currents comprising, a thermionic tube having input and output circuits coupled so as to form a feedback system, a second thermionic tube 160 having input and output circuits coupled so as to form a counter-feedback system, said systems having common input and output circuits, said feedback system being adjusted near the point of oscillation and means for periodically varying 165 the amount of feedback with respect to the amount of counter-feedback of said systems. 170
23. Apparatus for amplifying varying electric currents comprising, a thermionic tube feedback system having an input circuit and an output 175 circuit, a thermionic tube counter-feedback system having an input circuit and an output circuit, a portion of each of said two input circuits being common to both, and a portion of said two output circuits being common to both, means for periodically varying both the amount of feedback and the amount of counter-feedback of said system, comprising a source of energy of a frequency relatively low compared to the frequency of current to be amplified. 180

24. In a super-regenerative circuit an electron discharge tube regenerative system comprising a feedback circuit in combination with an electron discharge tube degenerative system comprising a 5. counter-feedback circuit, means for adjusting said regenerative system near the point of oscillation, a source of oscillations associated with both said systems and means controlled thereby for causing a periodic variation in the relation 10 between the amount of feedback in said feedback circuit and the amount of counter-feedback in said counter-feedback circuit. 80
25. In a super-regenerative receiver means for amplifying varying electric currents comprising 15 a feedback system and a counter-feedback system, said two systems having common input and output circuits, means for periodically varying both the amount of feedback and the amount of counter-feedback of said systems at some frequency relatively low compared to the frequency 20 of the current to be amplified, the amount of counter-feedback being of such an extent that it influences circuits coupled to said system but exterior thereto. 85
26. In apparatus for amplifying varying electric currents, an oscillatory circuit, means for periodically varying the total effective resistance of said circuit about a mean value greater than zero and means for making the maximum positive value of effective resistance of said circuit greater than the natural ohmic resistance of the oscillatory circuit. 90
27. In apparatus for amplifying varying electric currents, a resonant circuit, means for varying the net effective resistance of said resonant circuit periodically about a mean positive value at a frequency low compared to the natural frequency of said resonant circuit and means for making the maximum attained positive value of 30 effective resistance greater than the natural ohmic resistance of the resonant circuit. 95
28. In apparatus for amplifying varying electric currents, an oscillatory circuit comprising regenerative means and degenerative means, means for periodically varying the total effective resistance of said circuit about a mean value greater than zero and means comprising said degenerative means for making the maximum positive value of effective resistance of said circuit greater than the natural ohmic resistance thereof. 100
29. In a super-regenerative circuit, a pair of thermionic tubes having input and output circuits, the two input circuits having a common portion including a tuned circuit and the two 35 output circuits having a common portion including a load circuit, means for coupling a source of signal energy to said common tuned circuit, the signal energy transferred from said source to said tuned circuit being adapted to affect both thermionic tubes in like sense, a source of super-audible frequency waves differentially coupled to both said input circuits, means for coupling the output circuit of one of said thermionic devices to its input circuit in a sense to cause regeneration 40 and means for coupling the output and input circuits of the other thermionic device in a sense to cause de-generation. 105
30. In a super-regenerative circuit, a pair of thermionic tubes having input and output circuits, the two input circuits having a common portion including a tuned circuit and the two output circuits having a common portion including a load circuit, means for coupling a source of signal energy to said common tuned circuit, the 45 signal energy transferred from said source to said tuned circuit being adapted to affect both thermionic tubes in like sense, means for coupling the output and input circuits of the other thermionic device in a sense to cause de-generation, means for coupling the output and input circuits of the other thermionic device in a sense to cause regeneration, means for coupling the output and input circuits of the other thermionic device in a sense to cause degeneration, and means comprising a source of supersonic frequency waves for alternately rendering said two circuits inoperative. 110
31. In a super-regenerative receiver, a regenerative circuit including a space discharge device, damping means for said regenerative circuit comprising a degeneration circuit including a space discharge device, a source of signal energy coupled to both said circuits, a load common to both circuits and means for rendering said circuits alternately and periodically operative and inoperative. 115
32. The method of signal wave amplification which comprises building up oscillations to an intensity many times greater but proportional to the intensity of the signal wave to be amplified and periodically reducing to a substantial degree the intensity of the built up oscillations at a super-audible rate, the building up rate of the oscillations being substantially lower than the reduction rate. 120
33. In a super-regenerative circuit comprising at least one electronic tube provided with an input circuit and an output circuit, a source of interruption frequency voltage coupled to one of said circuits, an audio output circuit connected to the output of said device and means for opposing in said audio output circuit the current of interruption frequency fed thereto from said electronic tube. 125
34. In a super-regenerative circuit including at least one electronic discharge tube provided with input and output circuits, a source of interruption frequency voltage coupled to said input circuit, an audio output circuit connected to the output circuit of said device, and means for opposing in said audio output circuit the current of interruption frequency fed thereto through the 130 electronic tube, said means comprising a circuit arrangement including said audio output circuit and adapted to cause a current to flow through the audio output circuit of phase and magnitude to substantially neutralize the effect of said current of interruption frequency flowing through the audio-output circuit. 135
35. In a super-regenerative circuit including at least one electron discharge tube provided with an input circuit and an output circuit, an audio output circuit connected to the output circuit of said tube, a source of interruption frequency voltage connected to one of said electron discharge tube circuits so as to transfer interruption frequency energy thereto whereby energy of said interrupting frequency is present in the output circuit of said tube, means for opposing in said audio output circuit the energy of interruption frequency fed thereto from the tube output circuit comprising a circuit arrangement including 140 said audio output circuit and adapted to cause a current to flow through the audio output circuit of such phase and magnitude as to substantially neutralize the effect of the energy of interruption frequency transferred to the audio output circuit. 145
